UNITED STATES PATENT OFFICE

150,049

DESIGN FOR A COMBINED WRIST WATCH AND STRAP THEREFOR

Claude Arpels, New York, N. Y.

Application October 25, 1947, Serial No. 142,137

Term of patent 7 years

(Cl. D42—8)

To all whom it may concern:

Be it known that I, Claude Arpels, a citizen of the United States of America, residing in New York city, county of New York, and State of New York, have invented a new, original, and ornamental Design for a Combined Wrist Watch and Strap Therefor, of which the following is a specification, reference being had to the accompanying drawing, forming part thereof.

Fig. 1 is a plan view of a combined wrist watch and strap therefor, showing my new design.

Fig. 2 is an edge view thereof.

The dominant feature of my design resides in the continuity of the band portion through the face of the watch.

I claim:

The ornamental design for a combined wrist watch and strap therefor, substantially as shown and described.

CLAUDE ARPELS.
